JONAS CLARK, OF LOWELL, MASSACHUSETTS

Letters Patent No. 92,423, dated July 13, 1869.

IMPROVEMENT IN CIGAR-TIPS.

The Schedule referred to in these Letters Patent and making part of the same.

To all whom it may concern:

Be it known that I, JONAS CLARK, of Lowell, in the county of Middlesex, and State of Massachusetts, have invented a new and valuable Improvement in Cigar-Tips; and I do hereby declare that the following is a full, clear, and exact description of the construction and operation of the same, reference being had to the annexed drawings, making a part of this specification, and to the letters and figures of reference marked thereon.

Figure 1, of the drawings, is a longitudinal view of my invention, with the flat surface of the tip presenting.

Figure 2 is the same view, with the edge of the tip presenting.

Figures 3 and 4 are details.

My invention relates to the manufacture of cigars; and

It consists mainly in constructing, with the cigar, a mouth-piece or tip of paper and composition of a novel and useful character.

In the drawings, the body of the cigar is represented by the letter A, and the paper and composition-tip by the letter C.

The cigar is constructed in the usual manner, except that the small end is not twisted and pointed. In the place and stead of such twisting and pointing, I construct and affix the mouth-piece or tip C as shown.

My cigar-tips are constructed of paper covered with gum-shellac, and grained, and the centre thereof is filled with a composition combined substantially of the following ingredients, and according to the following formula, namely:

I take of ground plaster of Paris, or gypsum, three parts, and of wheat flour one part, and mix them to a stiff dough, using therefor a suitable quantity of cold water. This composition is passed into the paper forming the outside of the tip, properly perforated, and thoroughly dried. When this is done, the tip of paper and composition is attached to the cigar, by means of gum-shellac, and the cigar is ready for boxing, sale, and consumption.

Glue may be used to some extent in the above-named manufacture.

What I claim as my invention, and desire to secure by Letters Patent, is—

The cigar-tip herein described, constructed in the manner and of the materials substantially as specified:

In testimony that I claim the above, I have hereunto subscribed my name, in the presence of two witnesses.

JONAS CLARK.
